UNITED STATES PATENT OFFICE.

WALTER W. NICHOLS, OF MELROSE, MASSACHUSETTS.

MEASURING AND DISPENSING APPARATUS.

1,129,002.

Specification of Letters Patent. Patented Feb. 16, 1915.

Application filed December 2, 1912. Serial No. 734,464.

To all whom it may concern:

Be it known that I, WALTER W. NICHOLS, a citizen of the United States, and resident of Melrose, county of Middlesex, State of Massachusetts, have invented an Improvement in Measuring and Dispensing Apparatus, of which the following description, in connection with the accompanying drawings, is a specification, like letters on the drawings representing like parts.

This invention relates to automatic measuring or dispensing apparatus, being primarily intended to dispense liquids in measured quantities, and its object is to improve and perfect such devices. In dispensing apparatus of this class as heretofore made, such as that shown in my prior application Serial No. 703,213, filed June 12, 1912, the measuring faucet or valve was capable only of use in dispensing the measured amount and could not be used to allow the contents to pass therethrough except in measured quantities. Therefore it was impossible to allow a larger quantity than the measured amount to pass through such faucet at one time.

The object of my present invention is to provide a measuring faucet which can be employed to dispense a measured quantity and which also, at will, can be operated to allow a continuous flow through the faucet, thus combining in a single valve the advantages incident to both a measuring device and an ordinary faucet.

An important advantage of the present device is that, in large culinary devices such as coffee urns and the like, as many measured quantities or cups of coffee could be withdrawn as desired and then the faucet can be turned to permit the entire remaining contents to be drawn off at one time, instead of as formerly, requiring the entire contents to be withdrawn a single cup at a time. This is of great importance in any large sized receptacle, both for use, saving repeated operations to withdraw more than the measured capacity of the faucet, and for cleaning the device, where scalding water can be poured into it and allowed to run through continuously. In fact, without a faucet like that of my invention, permitting both a measured amount and a continuous flow therethrough, it is necessary to have two faucets in large sized receptacles or urns, one to draw off and clean the apparatus, and the other to dispense the contents.

In smaller receptacles, such as that shown in my prior application, it is possible either to upset the receptacle or to clean it from the top, but in the larger sized urns this operation is not feasible, and it is to the latter that my present device is especially applicable.

It is also an object of my present invention to provide an automatic drip preventing attachment, which will be effective to prevent any dripping from the discharging nozzle of the faucet when the valve is closed, by covering and closing the open end of the nozzle itself, such closing being operated automatically when the valve is closed. Preferably I provide this attachment, pivoted to the lower central part of the casing inclosing the working parts of the faucet, and so connect the attachment to the turning plug of the faucet that the operation of turning the plug to turn on or to shut off the flow therethrough, acts automatically to swing the cover for the nozzle into and out of operative position correspondingly.

Other details of construction, combinations of parts and novel features of the invention will be hereinafter more fully pointed out and claimed.

Referring to the drawings, illustrating a preferred embodiment of the invention,

Figure 1 is a side view of the entire device, with a portion of the outer casing broken away to show the turning plug; Fig. 2 is a view in cross section on the line 2—2 of Fig. 1; Fig. 3 is a plan view of the bottom of the faucet showing the drip preventing attachment; and Fig. 4 is a plan view on the line 4—4 of Fig. 1.

Any suitable form and size of faucet may be employed, but preferably I utilize a faucet and valve as shown, comprising a casing 1 having a spout or nozzle 2 and a threaded section 3, adapted to be screwed into a correspondingly threaded socket of the receptacle to which the faucet is to be attached. Preferably the casing has a conical or wedge shaped formation, and a correspondingly conical hollow plug 4 is fitted therein having a stem 5 to which is secured the handle 6 in any suitable manner held in position by the headed screw 7, as shown in Fig. 1. The casing 1 is also provided with a peripheral top flange 8, shown as threaded and in which is screwed a cover 9, having a suitable central aperture for the stem 5. Between the cover 9 and the top 10

of the hollow plug 4, I preferably employ an expansive spring 11, which is coiled around the stem 5, and bears between the under surface of the cover 9 and against the top surface 10 in order to hold the plug firmly seated in its conical bearing within the casing 1. This construction insures a firm and tight fit at all times during the turning of the plug in said casing. The inner wall of the casing 1 is formed, near its top with a groove 12, and a lug 13, formed on the exterior of the turning plug 4, is arranged to traverse said groove. The groove 12 is formed only partly around the casing 1, ending at 14 and 15 and therefore the rotation of the hollow plug 4 is confined within the limits of said groove. Preferably the end walls of the groove 14 and 15 are formed rounding, so as to act as a stop for the lug 13, and prevent the edge portions being hammered, or burred outwardly, which would scar and mar the face of the turning plug.

Arranged on the casing 1 at a point to intercept the plug 13 in its traversing action throughout the groove 12 is a thumb screw 16, threaded on to a correspondingly tapped socket 17, and having a smooth portion 18, without threads, arranged to project into the groove 12. When the thumb nut 16 is manipulated so that the portion 18 projects into said groove, the turning plug is limited in its rotation between the shoulders 15 and stop 18 by reason of the plug 13 bringing up against either the shoulder 15 or the stop 18. When, however, the thumb nut 16 is manipulated so that the portion 18 is withdrawn from the groove 12, then the turning plug 4 may be swung throughout the arc permitted by the entire length of the groove 12, as will be readily understood on reference to Fig. 2. The side wall of the turning plug 4 is provided with ports 19, 20, 21, and 22, the ports 19 and 21 being arranged in the upper portion to register with the opening 23 through the section 3, while the ports 20 and 22 are provided in the lower portion of the turning plug 4 to register with the discharge opening 24 of the nozzle 2. These various ports are so positioned with relation to the lug 13, that when the turning plug 4 is swung so that the lug 13 is in contact with the stop 15, the port 19 will register with the opening 23, and the remaining ports will be closed by contact with the walls of the casing 1. In this position the liquid contents of the receptacle to which the device is attached will flow through the ports 23 and 19 into the hollow cavity of the plug 4, filling up the same. Then when the plug is turned to the left, viewing Figs. 1 and 2, the port 23 will soon be closed by the wall 25 of the plug, and the port 20 will thereafter be opened into communication with the passage 24, and will fully register with the

same as the lug 13 is swung against the movable stop 18. When in this position, the remaining ports 19, 21 and 22 will be closed against the inner conical wall of the casing. When the contents measured by the capacity 70 of the hollow plug 4 have thus been discharged, the plug may be swung back and again filled and discharged as often as desired. However, when it is desired to allow a continuous flow of liquid through the 75 plug, the intermediate adjustable stop 16 is manipulated so as to withdraw the projecting portion 18 from the groove 12, and thus permit the plug 4 to be swung still farther to the left; and when swung so that the 80 lug 13 contacts with the end wall 14, then the port 21 will be in register with the intake portion 23, and the port 22 will be in register with the outlet 24, and thus a continuous flow is permitted through the 85 plug 4.

If desired, the ports 20 and 22 may be formed as a single large port, depending upon the inner wall of the casing 1 to limit the capacity of outflow, the main feature 90 being to permit either a measured quantity to be dispensed or a continuous flow to be allowed, through the same faucet. I believe that the combination of these two features in the same faucet is a distinct novelty 95 in the art to which this invention relates, and I therefore wish to claim the same broadly. My invention contemplates the provision of any suitable means to accomplish this combined object, but preferably I 100 utilize the construction herein shown, as thereby I am enabled to instantly change the faucet from a measuring to a continuous flow valve by simply moving the plug to a new position. Such movement could, of 105 course, be accomplished without the intermediate stop 18, but preferably such a stop is employed as it acts as a convenient means to prevent a too far movement of the plug, while the faucet is being utilized as a measuring apparatus. 110

I provide an attachment which operates as a dripless device or as a means to close the opening 24, and therefore to prevent any further flow or dripping from the nozzle 2 115 by means of a swinging plate or cover 26. This plate is of suitable size and contour to completely cover the discharge opening 24 in the nozzle 2, and has a portion extending rearwardly to enable it to be pivoted at 27 120 to a cross bar 28, secured to the bottom of the casing 1. The plate 26 extends beyond said pivot, having an aperture 29 arranged near its extreme inner end, in which aperture is loosely fitted a pin 30, tapped in a 125 socket 31 in the bottom of the plug 4. As the turning plug 4 is swung in order to be operated, the pin 30 swings this plate 26 upon its pivot 27, and opens or closes the discharge port 24 in the nozzle 2, as will be 130

clearly seen on reference to Fig. 3. The bar 28 and pin 30 are so positioned relatively with the ports in the turning plug 4 that as said plug is turned to allow the ports 19 and 5 23 to register, the plate 26 is in position to cover the delivery opening 24 and the nozzle 2. As the turning plug 4 is moved to swing the port 22 to register with the delivery opening 24, the cover 26 is swung on its 10 pivot 27 to free said opening and permit the contents to be discharged therethrough. Further movement of the plug 4, to permit continuous flow through the ports 21 and 22 of said plug simply acts to swing the plate 15 26 still farther from the nozzle 2. In order to permit the entire swing of the pin 30, a recess 32 is provided in the bar 28 of suitable depth to allow the turning plug 4 to be 20 swung throughout the extreme limits required by the length of the groove 12.

It will thus be seen that I have provided a faucet which will answer all the requirements and demands of a measuring or dispensing apparatus, and yet can be instantly 25 utilized as a faucet permitting continuous flow therethrough. Thus the contents of the receptacle may be entirely drawn off without delay, or, of course, a larger quantity than the measuring capacity of the turning 30 plug 4 can be withdrawn at any time.

Having described my invention, what I claim as new and desire to secure by Letters Patent is:

1. An apparatus of the kind described, 35 having provision to dispense either a measured quantity of liquid or to permit a continuous flow of liquid therethrough at will, comprising a hollow rotatable turning plug of predetermined capacity to dispense a 40 measured quantity, filling and discharging ports opening into said hollow plug, a casing fitting outside said plug, and permitting a relative rotative movement of the plug therein, said casing being formed with a 45 plurality of ports adapted to register with the ports of said plug during its rotative movement, the ports of both plug and casing being constructed, positioned and arranged to register at the initiation of rotative movement for filling the plug to dispense a 50 measured quantity, and by a further rotative movement in the same direction to provide a continuous flow through the plug.

2. An apparatus of the kind described, 55 having provision to dispense a measured quantity and to permit a continuous flow therethrough at will, comprising a hollow turning plug having a plurality of filling and discharge ports therein, a casing with 60 coöperating filling and discharge ports,

adapted to register with the ports of said plug, and stops to limit the relative rotative movement of said plug and casing, constructed and arranged to cause a measured quantity to be dispensed by the movement 65 of a quarter turn of said plug, and by a further movement of said plug in the same direction to permit a continuous flow therethrough.

3. An apparatus of the kind described, 70 comprising a casing having a plurality of ports, a hollow turning plug having a plurality of ports, registerable with the ports of said casing by a partial rotation of said plug, stops to limit the rotation of said plug 75 so arranged whereby the intake and discharge ports of both plug and casing register at each end of the limit of rotation of said plug, respectively, in combination with an adjustable stop intermediate said limit of rotation, adapted to render other of said intake and discharge ports in register.

4. An apparatus of the kind described, 80 comprising a casing having a plurality of ports and a hollow plug rotatable within 85 said casing, two positive stops to limit the relative rotation of said plug and casing, said plug having a predetermined capacity to receive and to dispense a measured quantity of liquid, in combination with means to 90 provide a continuous flow of liquid through said plug, both the dispensing of the predetermined quantity and the provision for a continuous flow being afforded between the 95 limit of movement permitted by said positive stops.

5. An apparatus of the kind described, 100 comprising a casing having a plurality of ports and a hollow plug rotatable within said casing, two positive stops to limit the 105 relative rotation of said plug and casing to approximately one quarter of a revolution, said plug having a predetermined capacity to receive and to dispense a measured quantity of liquid, in combination with means to 110 provide a continuous flow of liquid through said plug, both the dispensing of the predetermined quantity and the provision for a continuous flow being afforded between the limit of movement permitted by said positive stops within said quarter turn and by a continuing movement in one direction.

In testimony whereof, I have signed my name to this specification, in the presence of two subscribing witnesses.

WALTER W. NICHOLS.
